CONTROL BOX FOR MODEL AEROPLANES

Robert W. Vincent, Chappell, Nebr.

Application February 16, 1953, Serial No. 336,991

1 Claim. (Cl. 46—77)

This invention relates to an improved control means for model aeroplanes and relates more particularly to a control apparatus which is grasped and held in the one hand and actuated by the other.

An object of this invention is to provide a control box for model aeroplanes which embodies a simple yet efficient system of levers and links for manipulating the control lines of a model aeroplane.

Another object of this invention is to provide a control apparatus for model aeroplanes which includes an actuating lever operatively connected to a control link for actuating the latter to control and guide a model aeroplane during its flight.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the control apparatus showing its external construction;

Figure 2 is an end view of the control apparatus, portions being broken away to show details of its internal construction;

Figure 3 is a vertical section taken substantially along the plane of section line 3—3 in Figure 1;

Figure 4 is a bottom plan view of the apparatus with the bottom wall removed.

Referring now more particularly to the drawings, reference numeral 10 indicates generally the control box or casing which includes side walls 12, a forward end wall 14, a rearward end wall 16, a bottom wall 18, and the top wall 20. An elongated handle assembly 22 has its forward end 24 disposed within the casing and extends through a notch in the rear wall 16 laterally therefrom and terminates at its other end in a hand grip portion 26 by means of which the control assembly may be held and carried in one hand. As shown in Figure 4, a pair of screws 28 are provided for securing the handle assembly to the rear wall 16 although it will be apparent that this particular matter of securing is not essential.

The casing itself is preferably secured together by means of countersunk screws 30 at each corner to maintain its various component parts in assembled relation.

A pair of closely spaced guide blocks 32 are secured longitudinally on the top 20 and are laterally offset from its longitudinal center line, as shown most clearly in Figures 1 and 2. An actuating lever 34 is fulcrumed between the guard blocks by pin 36 and presents a manually actuated upper end 38 and a depending lower end 40 which extends downwardly within the confines of the casing. A link 42 is intermediately pivoted to the for-

2

ward end of the handle assembly by the screw 44 and washer 46 shown in Figure 2 and is provided at one side thereof with an aperture 48 for receiving a screw 50 secured in coextensive relation to the lower end of the actuating lever. Since the aperture 48 is substantially larger than the outer diameter of the screw 50, a washer 52 is disposed adjacent the screw head to prevent its disengagement from the aperture.

The opposite ends of the link are apertured to receive the angulated ends 54 of the control rods 56 whose free ends terminate in loops 58. These control rods extend substantially perpendicularly from the control lever and extend outwardly of the casing through the slots 60 in front wall 14.

In operation, the control rods are secured to the control wires of a model aeroplane and, while the aeroplane is in flight, the actuating lever 34 may be pivoted back and forth to manipulate the control rods in a push and pull relation to control the plane. During such manipulation of the aeroplane, the hand grip 26 is grasped by one hand of the user and the upper portion 38 of the actuating lever is manipulated with the other hand, as will be readily apparent. The loose engagement between the screw 50 and aperture 48 prevents any binding action between the actuating lever and the control link, thus providing for easy manipulation of the controls.

The assembly may be formed of any suitable material but is preferred to be constructed of wood or synthetic wood-like material to facilitate construction and maintain economical cost.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claim.

What is claimed as new is as follows:

A control apparatus for model aeroplanes comprising a casing having a pair of spaced side walls, a bottom and a top, an elongated handle member secured to said bottom and extending laterally of one side of the casing to present a hand grip portion, a link pivotally secured intermediate its ends to said handle between said side walls, said handle holding said link above said bottom, an actuating lever pivotally secured to said top along an axis normal to the pivotal connection between said link and said handle and having a lower end disposed within said casing and adjacent said link, means operatively connecting said lever to said link, and control rods connected to the opposite ends of said link for connection to the control wires of a model aeroplane for controlling the flight of the model aeroplane, said link being provided with an aperture adjacent the lower end of said lever and spaced from the pivotal connection between said link and said handle, and a screw secured to said lever loosely engaged within said aperture.
